PAGE 2

Fig 2

Fig 3

FIG. 1 is a front perspective view of an information storage unit showing our new design, the rear being plain and unornamented;

FIG. 2 is a right side elevational view, the left side being similar in appearance;

FIG. 3 is a top plan view;

FIG. 4 is a horizontal, sectional view of a portion of the information storage unit taken along the line 4—4 of FIG. 1; and

FIG. 5 is a vertical sectional view of the same portion of the information storage unit as FIG. 4, taken along the line 5—5 of FIG. 1.

We claim:

The ornamental design for an information storage unit, substantially as shown and described.
